UNITED STATES PATENT OFFICE

ADOLF SCHNEIDER, OF BROOKLYN, NEW YORK, ASSIGNOR OF ONE-HALF TO ARTHUR A. SCHNEIDER, OF EAST ORANGE, NEW JERSEY

BINDING POST

Application filed January 12, 1928. Serial No. 246,200.

This invention relates to fastening devices for wire, stays, cables, wire terminals and similar articles.

One object of my invention is to provide a simple, inexpensive and effective device of this kind which will prevent the disengagement of the clamped down article from its intended position.

Another object of my invention is to provide within my device, means for holding such articles attached thereto, under constant tension, and prevent the means whereby the article is fastened from voluntarily loosening.

The foregoing and further objects will be more fully apparent from the following description and the accompanying drawings, forming part of this invention, and in which:

Figure 1 illustrates a preferred form of my device,

Figure 2 is a vertical cross sectional view therethrough,

Figure 3 is a detail view of the lower portion of my device,

Figure 4 is a modified form thereof,

Figure 5 illustrates a modified form of my device, which is somewhat simplified in construction,

Figure 6 illustrates the application of my device to an attaching bolt,

Figure 7 illustrates a detail view of a part of Figure 6,

Figure 7a represents an expanded spring as used in my device,

Figure 8 illustrates a modified form of the device shown in Figure 5,

Figure 9 illustrates another modified form of my device shown in Figure 2,

Figure 10 is still another modification of my device in a simple form.

Referring to Figures 1, 2, 3 and 4, there is shown a body 10 which is bored and drilled for a bolt or screw 11 which passes through the body outwards. The head 12 of the screw or bolt remains within the body as shown in Figure 2. The bolt, passing through the

body, first is engaged by a terminal rest 13, which is stationary. The upper portion of the bolt is engaged by a specially designed nut 14, provided with recesses 15, adapted to be engaged by a specially designed key or wrench.

Nut 14 is provided with a spring seat 16 and a reduced portion 17 which serves as a guide or shank for coil spring 18. This spring is preferably so constructed that its upper reduced end, resting against seat 16, will freely glide thereupon no matter in which direction the nut is turned. The lower end portion of the spring, on the other hand, is pointy and adapted to engage the bottom of cup 19 when the nut is turned in the direction opposite to that in which the spring is wound, as will be explained presently. The cup forms the outer guide for the spring, and provides a clamping face 20, shown in detail in Figure 3, under which a terminal or the end of a wire or cable may be readily disposed, and by means of which the cable may be held in position, while the cable on the other hand holds cup 19 against rotation. The cable end passes out through slot 21, formed between two flanges 22 of the clamping face. A modified form of such clamping face is shown in Figure 4 where the clamping face 20' is shown to be radially knurled or grooved so as to produce a friction face adapted to engage the article to be clamped down.

In Figures 1 and 2, there is shown a wire 23 clamped down by means of nut 14, spring 18, and cup 19.

In the modified form of Figure 5, there will be seen a similar construction to that shown in Figure 2. In this case, again a block of material 24 is hollowed out at 25, to receive head 26 of bolt 27. The latter is engaged again by a terminal seat 28, adapted to form a rest for a terminal 29 of cable 30. This terminal is engaged by the lower sharp end of spring 31, which is held down by means of nut 32. This nut is reduced at 33

and is engaged by the spring, and a seat 34 is provided for the upper end of the spring, which is rounded off and adapted to glidably engage the face of seat 34. In this construction, the outer cup for the spring is eliminated and the lower end of the spring engages the terminal 29 directly.

In Figure 6, there is shown still another modified form in which case a body 35 is shown reinforced by a plate 36, which is provided with a threaded hole engaged by the threaded end of bolt 37. At the upper end of the bolt there is provided a head 38, which is recessed at 39, providing a seat 40 for the spring 41. Below the lower end of the spring 41 is again either a cable terminal or wire end, indicated at 42, which rests with its lower face against an anchor plate 43. This plate is shown in detail in Figure 7. It is equipped with prongs 44, adapted to be impressed into the material of the body 35, thus providing a resting face for terminal or wire 42. The upper dull end of spring 41 engages the recessed seat portion 40 of the head of the bolt, while the lower sharp end of the spring engages the terminal or wire 42 directly.

Figure 8 shows another modified form of my device in which a similar construction to that in Figure 6 is illustrated with the exception that instead of a bolt with the head permanently attached thereto, a stud is employed which is threaded at both ends. A block of material 45 is shown to be reinforced by a plate 46, which is provided with a threaded hole engaged by the lower threaded end of stud 47.

The upper end of the stud passes through a washer 48, upon which rests a terminal or wire end 49. Engaging that wire end is the lower end of spring 50, its upper end being seated against the seating portion 51 of nut 52, which is reduced at 53, forming a shank engaged by the spring.

In Figure 9, there is shown a modified form of my device from that illustrated in Figure 2. In this case a block of material 53 is again shown to have a depression 54, housing head 55 of bolt 56. The upper threaded part of bolt 56 is engaged by a nut 57, which is recessed at 58, providing a seat 59 for a spring 60. The recess is wide enough to accommodate a cup 61. The upper open end of the cup and the lower peripheral edge 62 of the nut are so arranged as to prevent the cup from disengaging the nut, thus also preventing the spring 60 from falling out. The lower face of the cup may be again provided with means for clamping or otherwise holding the wire end 63 or a cable terminal in place.

A still further modified form is shown in Figure 10, where a plate 64 is seen engaged by the threaded end 65 of bolt 66. Disposed between the head 67 of the bolt or screw and

the inner face of the cup 68, is the compressed expansion spring 69, the lower end of which is again sharp and adapted to frictionally engage the inner bottom face of the cup. The outer bottom face of the cup engages again a terminal or wire 70.

Operation

All of the above described devices are adapted to hold or clamp articles by the action of a compressed expansion spring which is clearly shown in its normal, expanded position in Figure 7a.

When the shank, forming either the reduced portion of the nut or the smooth portion of the bolt, which is engaged by the coiled spring, is turned in the direction in which the spring is wound, the friction between the inner face of the spring and the outer face of the shank causes the tightening of the spring around the shank, in other words, in the direction from without to within.

This function of the spring, considered in connection with the cup engaging the outer surface of the spring, will cause a movement of the spring in the direction from the inner face of the cup. In other words, there will be practically no friction or a lessened friction between the inner surface of the cup and the outer surface of the spring at the time when the nut or bolt is turned in the direction in which the coiled spring is wound.

When this operation is reversed and the bolt or nut is turned in the direction opposite to that in which the coiled spring is wound, the lower sharpened end of the spring, will, so-to-speak, imbed or dig itself into the face of the cup and cause the stopping of the spring against rotation while the shank is turned. In consequence thereof, the friction between the shank and the coiled spring is lessened or eliminated. On the other hand, friction is created between the inner face of the cup and the outer face of the spring. In this manner the friction created between the outer face of the spring, and inner face of the cup, will cause the spring and cup to stand still, while the nut or bolt is permitted to freely turn in the direction opposite to that in which the spring is wound, there being no friction between the inner spring face and the shank. Thus, the loosening of the nut and eventually the subsequent loosening of the cup is accomplished, whereafter the article may be readily removed from below the cup.

The above description applies to the constructions shown in Figures 1, 2, 9 and 10.

The same or similar function applies to the construction shown in Figures 5, 6 and 8, with the difference that the spring is not lodged in a cup. In all other respects the function of the spring in conjunction with the shank remains identical.

In order that the above assertion be made clear, I might repeat that in the event the nut is turned in the direction in which the spring is wound, the latter will be drawn together by the friction between the shank and the inner face of the spring. When the bolt or nut is again turned in opposite direction, the lower sharpened end of the spring digs itself, so-to-speak, into the article clamped, and permits the spring to loosen itself from the shank portion of either the nut or bolt, while allowing the nut or bolt to be readily loosened until the spring itself becomes loose enough so that the article clamped thereunder may be removed.

Particular attention is called to the construction shown in Figures 1, 2 and 9, and especially the latter figure, where a complete unit is formed between the nut and cup with the spring enclosed by both. The entire combination may be handled as one unit and attached to or detached from a bolt or screw as such unit. The function of the spring is identical in all forms shown, i. e., when the nut or bolt provided with a cylindrical shank portion is turned forcibly in the direction in which the spring is coiled, the spring, having tightened itself around the shank portion, will travel with the nut or bolt. When however, the nut or bolt is forcibly turned in opposite direction to that in which the spring is wound, the spring will remain stationary while it loosens itself from the shank member until the entire device is loosened sufficiently to remove the article clamped thereby.

It is obvious that this device is applicable for fastening articles in the electric field where wires, cables and terminals transmitted current to light, power or ignition devices are depending upon constant and positive contact. Especially in connection with aeroplanes, automobiles, railroads and machinery and devices subjected to extreme shocks, or vibrations, my device will find widest use.

While I have shown certain specific forms of my invention, be it understood that variations and changes in design and modifications may be made to meet various conditions. In the drawings there are shown devices with round coil springs. Those springs may be made of various sections, as for instance, square or flat for heavy duty service, while the principle of operation remains the same.

Having thus described my invention, I claim:

1. In a binding-post comprising a stationary screw-stud protruding from a terminal-rest and a revolvable nut-member having a reduced extension, a coil-spring surrounding the said screw-stud, the said coil-spring having at least two turns wound in a direction opposite to the direction of the threads of said

screw-stud, said spring being slightly tapered and placed with its smaller end around said reduced extension of the nut-member in such a manner as to grip the sides of said extension, and its other end engaging a member resting on the terminal to be fastened. 70

2. In a binding-post comprising a stationary screw-stud protruding from a terminal-rest and a revolvable nut-member having a reduced extension, a coil-spring surrounding said screw-stud, said coil-spring having at least two turns wound in a direction opposite to the direction of the threads of said screw-stud, a cup-shaped member below said spring, said spring being slightly tapered and placed with its smaller end tightly engaged around said reduced extension of the nut-member and with its larger end entered in said cup-shaped member, said cup-shaped member being forced by the tension of said spring in holding engagement with the terminal to be fastened. 75 80

3. For engagement with a screw-stud protruding from a terminal-rest, a binding member comprising a nut having a reduced shank-extension, an upwardly tapered coil-spring, one end of said coil-spring being disposed in constricted gripping engagement about said shank-extension, and a flat bottomed cup-shaped member into which the other end of said spring is snugly fitted, and said cup-shaped member having a bottom friction-surface adapted to grip the terminal to be fastened. 90 95

4. For engagement with a screw-stud protruding from a terminal-rest, a binding member comprising a nut having a reduced shank-extension, an upwardly tapered coil-spring having at least two turns wound in a direction opposite to the direction of the threads of the screw-stud, the upper end of said coil-spring being disposed in constricted engagement about said shank extension, and a cup-shaped member into which the lower end of said spring is snugly fitted, said cup-shaped member being adapted to grip the terminal to be fastened. 100 105

5. In a binding-post, a nut-member for engagement with a screw-stud protruding from a terminal-rest, said nut-member having a reduced shank at its under side, an upwardly tapered multturn coil-spring with its upper end in constricted gripping engagement with said reduced shank of said nut-member, and said coil-spring having flat bottomed means at its lower end for gripping the terminal to be fastened. 115 120

6. Locking means for screw or bolt-devices for fastening articles comprising a threaded stationary member, a nut-member engaging the latter and having a reduced shank-extension, an expansion coil-spring wound in a direction opposite to the direction of the threads of said stationary member, one end of which grippingly surrounds the said shank- 125 130

extension of said nut-member and a centrally perforated cup-shaped member tightly surrounding the other end of said expansion-coil-spring and adapted to grip the article to be fastened.

7. Locking means for screw or bolt devices for fastening articles, comprising a threaded stationary member, a nut-member engaging the latter and having a reduced shank-extension, and an expansion-coil-spring wound in a direction opposite to the direction of the threads of said stationary member, one end of which grips said shank-extension and the other end of which is provided with means for frictionally gripping the article to be fastened.

8. In combination with a turnable screw-threaded fastening device having a smooth cylindrical portion, a tapered coil-spring, the small end of said spring being disposed in constricted gripping engagement about the smooth cylindrical portion of said fastening device, and the opposite end of said spring being adapted to thrust toward means to be fastened by the device.

9. In combination with a turnable screw-threaded fastening device having a smooth cylindrical portion, a tapered coil-spring, the small end of said spring being disposed in constricted gripping engagement about the smooth cylindrical portion of said fastening device, the convolutions of said spring being pitched in a direction opposite to the unscrewing direction of rotation of said fastening device, whereby unscrewing movement of the device tends to more tightly constrict the small end of said spring in gripping relation to the fastening device, and the opposite end of said spring being adapted to thrust toward means to be fastened by the device.

Signed at New York in the county of New York and State of New York this 31st day of December A. D. 1927.

ADOLF SCHNEIDER.
